UNITED STATES PATENT OFFICE.

ARCHIBALD FERGUSON REDDIE, OF PHILADELPHIA, PENNSYLVANIA,
ASSIGNOR TO McCALLUM & McCALLUM, OF SAME PLACE.

DESIGN FOR CARPET.

SPECIFICATION forming part of Design No. 24,413, dated June 18, 1895.

Application filed March 4, 1895. Serial No. 540,531. Term of patent 3½ years.

To all whom it may concern:

Be it known that I, ARCHIBALD FERGUSON REDDIE, a citizen of the United States, residing at the city of Philadelphia, in the county of Philadelphia and State of Pennsylvania, have invented and produced a new and original Design for a Carpet or other Fabric, of which the following is a specification, reference being had more particularly to the accompanying drawing, illustrating the same and forming part hereof.

A clear understanding of that which constitutes my invention and imparts a peculiar or distinctive appearance to the carpet to which it is applied is readily understood by an inspection of the accompanying drawing, in which—

a is the body, and *b* the border, and *a* and *b*, taken together, constitute a complete carpeting.

Obviously the design illustrated in the drawing may be wrought in or applied to Brussels, velvet, Wilton or other carpeting and

made to appear in various colors, tints or combinations of them.

The leading or characteristic feature of my design may be said to be the ornamentation *c*, displayed upon a background *d*, and in the drawing, associated with a band *e*, and with a dragon or griffin *f*.

What I claim as my invention, and desire to secure by Letters Patent, is—

1. In a design for a carpet the body *a*, substantially as shown.
2. In a design for a carpet the border *b*, substantially as shown.
3. The design for a carpet consisting of the body *a*, and border *b*, substantially as represented in the accompanying drawing.

In testimony whereof I have hereunto signed my name in the presence of two witnesses.

ARCHIBALD FERGUSON REDDIE.
